UNITED STATES PATENT OFFICE,

REUBEN C. RUTHERFORD, OF QUINCY, ILLINOIS.

TELEGRAPH-SOUNDER.

SPECIFICATION forming part of Letters Patent No. 357,789, dated February 15, 1887.
Application filed May 25, 1886. Serial No. 203,231. (No model.)

To all whom it may concern:

Be it known that I, REUBEN C. RUTHERFORD, of Quincy, in the county of Adams and State of Illinois, have invented new and useful Improvements in Loud and Secret Telegraph-Sounders, of which the following is a specification, reference being had to the annexed drawings, forming a part thereof, in which—

10 Figure 1 is a plan view of my improved sounder, the cover being removed. Fig. 2 is a transverse section taken on line *x* *x* in Fig. 1. Fig. 3 is a side elevation.

Similar letters of reference indicate corresponding parts in the different figures of the drawings.

The object of my invention is to construct a portable telegraph-sounder which may be employed for receiving telegraphic messages either directly from the line or through a relay and local circuit, the sounder being arranged so as to be capable of producing at the will of the operator either signals audible at a distance from the instrument or very light 25 signals capable of being heard only by the application of the instrument to the ear of the operator.

My invention consists in a sounder provided with an armature-lever carrying two hammers, 30 and in the combination therewith of a casing containing the sounder and provided with an adjustable resonant cover for receiving the blows of the hammer.

It also consists in an adjustable slide for 35 regulating the strokes of the armature-lever when the instrument is arranged for producing secret signals.

The circular casing A, which contains the working parts of the instrument, is provided 40 with an externally-screw-threaded flange, *a*, to which is fitted the screw-threaded rim *b* of the cover B. The rim *b* is of sufficient width to support the cover B a short distance from the flange *a*, and between the flange *a* and the 45 cover B series of perforations, *c*, are formed in the rim *b*. Within the casing A is secured an electro-magnet, D, of the usual description, but made of small size and adapted to the casing A. Above the poles of the magnet D is 50 supported an armature, E, with one edge ar-

ranged in contact with the poles of the magnet to insure the prompt action of the armature. To the ends of the armature E are secured arms *d*, which both project in the same direction beyond the edge of the armature, and are 55 provided with conical cavities exactly opposite the edge of the armature for receiving the pivotal screws *e*, upon which the armature turns.

The screws *e* are supported by brackets *f*, 60 secured to the top of the flange *a*, and are provided with jam-nuts *g* for holding them in adjustment. The armature E carries a lever, F, having a long arm, *h*, and a short arm, *i*. The magnet D is located at one side of the center 65 of the casing A, and the arms *h* *i* of the lever F project slightly above the upper edge of the casing A. The arms *h* *i* carry hammers *j* *j'*, which are capable of being brought into contact with the inner surface of the cover B in 70 alternation. With the armature-lever F is connected one end of a retractile spiral spring, *k*, the opposite end of which is connected with the threaded rod *l*, which extends through the bottom of the casing A and receives an adjust- 75 ing-screw, *m*.

In the side of the casing A opposite the magnet D is formed a slot, *n*, through which projects a clamping-screw, carrying on its inner end a plate, *o*, and on its outer end outside of the casing a curved plate, *p*, and knob *q*. The plate *o* is slotted from one of its edges to receive the end of the armature-lever F, and the upper edge of the slot is inclined, making the slot wider at the open end than at the opposite end, so that by moving the plate *o* the distance through which the lever F can be moved by the armature may be varied. When the end of the armature is in the open and wider end of the slot, it is allowed to move 85 sufficiently to give the loudest sound required for secret telegraphy, and as the plate *o* is moved forward over the lever the movement of the lever will be still more limited, and when the plate is moved so as to receive the 90 lever in the narrow end of the slot the lever will be prevented from moving.

To the outer surface of the casing A is applied a curved slotted plate, *r*, which is clamped to the side of the case by a nut, *s*, turning on 100

a stud, *t*, projecting through the slot of the plate. The plate *r* limits the movement of the plate *p*, so that when the operator has once adjusted his instrument for secret telegraphy it may be afterward quickly shifted from such an adjustment to that required for loud signaling and rearranged for secret telegraphy without readjusting the instrument.

The terminals of the magnet *D* are connected with the binding-posts *u u*, which receive the current through flexible conductors *v v*. When electrical pulsations pass through the magnet *D*, the armature *E* is alternately attracted and released, and when the lever *F* is disengaged from the plate *o* every approach of the armature *E* to the poles of the magnet *D* causes the hammer *j*, carried by the lever *F*, to strike on the inner surface of the cover *B*, and when the armature *E* is released the spring *k* causes the lever to tilt, and brings the hammer *j'*, carried by the shorter arm of the lever, against the inner surface of the cover *B*, producing a sound corresponding to the return-stroke of the armature-lever in an ordinary sounder. The force of the blows of the hammer may be regulated by changing the tension of the spring *k*, and also by screwing down the cover *B* on the case *A*.

When it is desired to shift the instrument from the adjustment required for loud signaling to that required for secret telegraphy, the slotted plate *o* is brought into engagement with the lever *F*, when the lever will alternately strike the edges of the plate above and below the slot, or will strike the inclined arm *w* at the upper side of the slot on the upstroke of the lever and strike the flange *a* on the back stroke.

When the instrument is used in an office employing many operators, the confusion arising from the clicking of a large number of instruments may be entirely avoided by shifting the instrument from the adjustment for loud signaling to the adjustment for secret telegraphy in the manner already described,

the call-signal being received before shifting the instrument.

The apertures *c* in the rim of the cover *B* permit of the escape of sound from the interior of the case *A*.

Having thus described my invention, what I claim as new, and desire to secure by Letters Patent, is—

1. The combination, with the electro-magnet and armature-lever carrying an armature within the influence of the magnet, of a resonant case inclosing the magnet and armature-lever, and having a resonant adjustable cover rigidly held at its periphery and arranged to receive the blows of the armature-lever and to protect the armature-lever and top of the magnet, substantially as herein shown and described. 55

2. The combination, with the armature-lever *F*, of a sliding plate, *o*, having an inclined surface for regulating the stroke of the lever, substantially as shown and described. 65

3. The combination, with the armature-lever *F* and sliding plate *o*, for regulating the stroke of the lever, of an adjustable stop-plate, *r*, substantially as herein shown and described. 70

4. The combination, with the magnet *D*, armature *E*, and lever *F*, provided with hammers *j j'*, of a resonant case, *A*, provided with the adjustable cover *B*, the slotted sliding plate *o*, and the adjustable stop-plate *r*, substantially as shown and described. 75

5. The combination, in a telegraph-sounder, of an armature-lever, *F*, provided with hammers *j j'*, and the casing *A*, having the resonant cover *B*, substantially as shown and described. 80

6. The combination, with the magnet *D* and armature-lever *F*, of the cover *B*, having the rim *b*, provided with series of apertures *c*, substantially as shown and described.

REUBEN C. RUTHERFORD.
